SNUBBED RAILWAY TRUCK

Glenn F. Couch, Bergen, N.Y., assignor to Symington Wayne Corporation, Salisbury, Md., a corporation of Maryland

Filed Jan. 22, 1959, Ser. No. 788,306

6 Claims. (Cl. 105—197)

This invention relates to snubbed railway trucks and has for its primary object the provision of an improved assembly for such a truck having inbuilt snubbing means for snubbing oscillation of supporting coil springs.

Another object of the invention is to provide an improved assembly wherein wedge means, pocketed in one of a pair of coil spring supported and supporting members are spring-urged both horizontally and vertically into engagement with angularly related friction surfaces carried by the members, thereby snubbing oscillations of the supporting springs, while preventing chucking of the wedge means relative to the member in which they are pocketed on relative vertical movement of the members.

An additional object of the invention is to provide an assembly wherein a wedge, carried by one of a pair of coil spring supported and supporting members, spring-urged, horizontally against one member and vertically against the other, by the engagement of an oblique wedging face on the wedge and a correspondingly oblique wedging surface on the member carrying the wedge, the wedging face and surface being inclined relative to friction surfaces on both members against which the wedge is urged, as well as relative to the wedge spring.

A further object of the invention is to provide a bolster assembly having bolster-carried wedges spring-urged horizontally and vertically against the side frame and bolster, wherein the extent of retraction of the wedges into the bolster is limited to protect the wedge springs and the wedges and readily lockable in retracted position for assembly and disassembly of the bolster and side frame.

Another object of the invention is to provide a bolster assembly having a wedge at each side at either end, wherein the wedges not only are wedged both horizontally and vertically under force of associated wedge springs but are identical and interchangeable.

Other objects and advantages of the invention will appear hereinafter in the detailed description, be particularly pointed out in the appended claims and be illustrated in the accompanying drawings, in which:

FIGURE 1 is a fragmentary horizontal sectional view on an enlarged scale, taken along the lines 1—1 of FIGURE 2;

FIGURE 2 is a fragmentary view, partly in elevation and partly in vertical section, taken along the lines 2—2 of FIGURE 1, of a railway truck embodying a preferred form of the bolster assembly of the present invention; and

FIGURE 3 is a fragmentary vertical sectional view taken along the lines 3—3 of FIGURE 1.

Referring now in detail to the drawings in which like reference characters designate like parts, the improved assembly of the present invention, designated as 1, is adapted for either of a pair of coil spring supported and supporting members for snubbing oscillations of the supporting coil springs. As exemplary of the invention, the assembly has been illustrated as a bolster assembly 1 connected at either end to a side frame 2 and having its bolster 3 supported thereon, in a bolster opening 4 by suitable supporting coil springs, indicated diagrammatically at 5. Since the bolster assembly 1 is the same at both ends only one end portion and the related part of the side frame 2 connected thereto are required for understanding of the invention and the illustration has been so limited.

Typical of those to which the illustrated bolster as-

2

sembly 1 is applicable, the side frame 2 has its bolster opening 4 enlarged, as at 6, to pass the bolster 3 during assembly and disassembly and is bounded at the sides over the portion in which the bolster normally rides, by transversely spaced, upstanding guide columns 7, each carrying or having formed on it one of a pair of correspondingly spaced friction surfaces 8. Preferably vertically directed and substantially parallel, the friction surfaces 8 will usually be formed, as here, on wear plates 9 fixed or secured to the guide columns 7.

Limited in inboard and outboard movement relative to the side frame 2, conventionally by a pair of longitudinally spaced inboard and outboard guide lugs 10 outstanding from each of its sides 11 and embracing or straddling the adjoining or related guide columns 7, the bolster 3 of the bolster assembly 1 has in each side a pocket or recess 12 confronting and opening between the related pair of guide lugs towards the friction surface 8 of the adjoining guide column 7. Seated in each of these pockets 12 are wedge or friction shoe means, preferably in the form of a single wedge-shaped wedge or friction shoe 13 having an outer side wall 14 on which is formed or carried a substantially vertically directed friction face 15 disposed longitudinally of the bolster 3 and confronting and frictionally engageable with the correspondingly directed and disposed friction surface 8 of the adjoining guide column. Desirably, the outer side wall 14 of each wedge 13 is of greater vertical extent than the pocket 12 in which the wedge seats and both vertically overlaps and is normally spaced outwardly from the lateral edges 16 of the top and bottom walls 17 and 18, respectively, of the bolster 3 so as to enable these edges to act as stops to limit the extent to which the wedge can retract or be compressed into its pocket.

In addition to its outer friction face 15, each of the wedges 13 has either a top or upper or a bottom or lower friction face 19 disposed at an angle or angularly related to the first friction face and preferably substantially at right angles or normal thereto so as to be horizontally directed or disposed. Each of these substantially horizontally directed friction faces 19 in turn confronts and is adapted to frictionally engage a correspondingly, preferably horizontally directed friction surface 20 in and defining, appropriately, the top or upper or the bottom or lower extremity of the pocket 12 seating the wedge. There also is provided on an inner side of each wedge a wedging face 21 which is oblique or doubly inclined and, specifically, is inclined or sloped outwardly of the associated pocket toward its vertically directed outer friction face 15 and at an acute angle to its horizontally directed, upper or lower friction face 19. Converging or tapering either inboardly or, as here, outboardly toward the outer friction face 15, the wedging face 21 of each wedge 13 confronts and engages a correspondingly inclined or sloped, oblique wedging surface 22 which includes with the friction surface 20 in the same pocket an acute angle and conveniently may merge outwardly with and is inclined or sloped inwardly of the bolster away from the column-engaging face 23 of the outboard or inboard guide lug 10 appropriate for the particular wedge, within the bolster, terminates intermediate the longitudinal confines of the associated pair of guide lugs.

For wedging the wedging face 21 of each wedge 13 on or against the wedging surface 22 in the associated pocket 12, there is provided resilient or yieldable means, preferably in the form of a double coil spring 24 acting between and seating at its opposite ends against confronting or opposed spring seats, one, 25, formed, to conserve space, in rather than on the wedge 13 and the other, 26, formed in the pocket 12. Projecting into the wedge and preferably acting horizontally rather than vertically because of the greater space available longitudinally of the bolster 3,

and thus, with the wedging face 21 and wedging surface 22, substantially horizontally extending the wedge spring 24 perforce is inclined or angularly related to both the wedging face and the wedging surface, therethrough to exert a wedging action on the wedge, but may be directed either parallel or, as in the illustrated embodiment, at an angle to the longitudinal center line of the bolster. The choice in the direction of the wedge spring 24 depends on the force desired to be exerted between the vertically directed friction face 15 on the wedge 13 and the friction surface 8 on the adjoining guide column 7, as determined by the horizontal inclination of the wedging surface 22 in the pocket 12 relative to the vertically directed surface carried by the guide column and the strength of the spring and its inclination relative to the wedging surface 22.

In the preferred form of the bolster assembly 1, the inner or inner side wall 27 of each pocket 12 is interrupted and divided into two portions, one 28 carrying the wedging surface 22 and the other 29 closing the inner side of the socket 30 within the pocket in which the spring 24 is partly contained, these portions being separated or spaced by an intervening or intermediate slot 31 opening from the pocket transversely into the bolster 3. Projecting through this slot 31 into inwardly overlapping or interlocking relation with the socket-defining portion 29 of the inner wall 27 of the pocket is an inner end portion or tail 32 of the wedge formed by an inner extension or projection of its inner side wall 33 on which is carried or formed its wedging face 21. This overlap or interlock between the inner end portion 32 of the wedge and the inner wall 27 of its pocket 12, which obtains when the bolster assembly 1 is in assembled position between the guide columns 7, is readily maintainable during assembly and disassembly of the bolster 3 and side frame 2 by providing horizontally directed apertures 34 and 34a in the inner walls 27 and 33 of the wedge 13 and pocket 12, respectively, which will register or align on compression of the associated wedge spring 24 for receiving a temporary assembly or retainer pin (not shown), thus ensuring that each wedge will remain in its pocket when, either prior to installation or on subsequent removal, the bolster assembly is disengaged from the side frame 2. With the preferred bolster 3 open-ended, the alignable apertures 34 and 34a are readily accessible for insertion and removal of the temporary retainer pins particularly if, as in the disclosed embodiment, the wedge springs 24 act outboardly on the wedges 13 so that the wedging surface carrying portion 28 of the inner wall 27 of each pocket is disposed toward the outboard side of the pocket and adjacent the outboard end 35 of the bolster.

Not only may the wedge springs 24 at either end of the bolster 3 act on the associated wedges in the same inboard or outboard direction but, if desired, one may act inboardly and the other outboardly. Also, the arrangement at either end of the bolster assembly 1 may be symmetrical about the longitudinal center line of the bolster 3, with the pockets 12 and wedges 13 at that end counterpart. However, the illustrated nonsymmetrical arrangement is preferred, in which the pockets and wedges are identical but relatively inverted and the wedging surfaces 22 in the pockets at each end diverge relatively toward one or the other end of the bolster and at the same angle to the bolster's longitudinal center line. This construction has the advantages that the cores used for the pockets in casting the bolster are identical and the wedges, since identical, are interchangeable. In any of these alternatives, it is preferred that the wedging face 21 and top or bottom friction face 19 on each wedge 13 be crowned so as to permit limited rocking between these faces and the top or bottom friction surface 20 and wedging face 21 in the associated pocket, so as to maintain surface contact between the vertically directed friction face 15 of the wedge and the column-carried friction sur-

face 8 which it confronts, despite limited angling in service of the bolster 3 relative to the side frame 2.

Whether the bolster assembly 1 is constructed in accordance with one or another of the several alternatives, the double inclination of the wedging surface 22 in each pocket 12 enables the wedge spring 24 in that pocket to wedge the associated wedge 13 not only outwardly, horizontally, against the adjoining column-carried friction surface 8, but vertically or upwardly or downwardly, depending on the particular pocket, against the substantially horizontal friction surface 20 in that pocket. Consequently, the wedges are enabled to frictionally resist and thus dampen the oscillations of the supporting springs 24 and at the same time are held against chucking in one or the other of the vertical extremities of their pockets during vertical movement of the bolster relative to the side frame. At the same time, the force of each wedge spring 24 which urges its wedge 13 outwardly, transversely of the bolster, against the related guide column 7, also renders the truck, bolster and side frame self-squaring by resisting retraction of the wedges into the bolster under forces tending to angle the bolster relative to the side frame.

From the above detailed description, it will be apparent that there has been provided an improved bolster assembly having inbuilt snubbing means which effectively dampen oscillations of the supporting springs, render the truck of which the assembly is a part self-squaring and are themselves held against chucking on relative vertical movement between the bolster and side frame. It should be understood that the described and disclosed embodiment is merely exemplary of the invention and that all modifications are intended to be included which do not depart from either the spirit of the invention or the scope of the appended claims.

Having described my invention, I claim:

1. In a snubbed railway truck having a side frame carrying supporting coil springs and on a guide column thereof a vertically directed friction surface, a bolster assembly comprising a bolster supported on said springs and having a pocket in a side thereof opening toward said friction surface, a horizontally directed friction surface defining a vertical extremity of said pocket, an oblique wedging surface in said pocket and inclined outwardly thereof toward said vertically directed friction surface and at an acute angle to said horizontally directed friction surface, a slot in an inner wall of said pocket inwardly of said wedging surface, wedge means in said pocket and having vertically and horizontally directed friction faces frictionally engageable respectively with said vertically and horizontally directed friction surfaces, an oblique wedging face on said wedge means inclined in correspondence with and engaging said wedging surface, means on said wedge means normally projecting through said slot and overlapping said inner wall rearwardly thereof, and spring means in said pocket and inclined relative to said wedging and vertical friction surfaces, said spring means acting on said wedge means and through said wedging face and surface for urging said friction faces and surfaces into frictional engagement.

2. In a snubbed railway truck having a side frame carrying supporting coil springs and on a guide column thereof a vertically directed friction surface, a bolster assembly comprising a bolster supported on said springs and having a pocket in a side thereof opening toward said friction surface, a horizontally directed friction surface defining a vertical extremity of said pocket, an oblique wedging surface in said pocket and inclined outwardly thereof toward said vertically directed friction surface and at an acute angle to said horizontally directed friction surface, a wedge in said pocket and having vertically and horizontally directed friction faces frictionally engageable respectively with said vertically and horizontally directed friction surfaces, an oblique wedging face on said wedge inclined in correspondence with and engaging said wedging surface, spring means in said pocket and acting on said

wedge and through said wedging face and surface for urging said friction faces and surfaces into frictional engagement, a slot in an inner wall of said pocket and opening into said bolster, means on said wedge normally extending through said slot and inwardly overlapping an adjoining portion of said inner wall, and apertures in said inner wall and a confronting wall of said wedge, said apertures being alignable on retraction of said wedge into said pocket for receiving a retaining pin and cooperating with said overlap for holding said wedge in retracted position in said pocket during assembly and disassembly of said bolster and side frame.

3. In a snubbed railway truck having a side frame carrying supporting coil springs and on a guide column thereof a vertically directed friction surface, a bolster assembly comprising an open-ended bolster supported on said springs and having a pocket in a side thereof opening toward said friction surface, a horizontally directed friction surface defining a vertical extremity of said pocket, an oblique wedging surface in said pocket and inclined outwardly thereof toward said vertically directed friction surface and at an acute angle to said horizontally directed friction surface, a wedge in said pocket and having vertically and horizontally directed friction faces frictionally engageable respectively with said vertically and horizontally directed friction surfaces, an oblique wedging face on said wedge inclined in correspondence with and engaging said wedging surface, spring means in said pocket and acting on said wedge and through said wedging face and surface for urging said wedge outwardly and vertically of said pocket and said friction faces and surfaces into frictional engagement, stop means on said wedge and engageable with said bolster for limiting inward movement of said wedge relative to said pocket against the force of said spring means, means normally interlocking said wedge and bolster, and horizontally directed alignable apertures in said wedge and bolster and accessible through an open end of said bolster for receiving a retaining pin and cooperating with said interlocking means to lock said wedge in retracted position during assembly and disassembly of said bolster and side frame.

4. In a snubbed railway truck having a side frame carrying supporting coil springs and on a guide column thereof a vertically directed friction surface, a bolster assembly comprising a bolster supported on said springs and having a pocket in a side thereof opening toward said friction surface, a horizontally directed friction surface defining a vertical extremity of said pocket, an oblique wedging surface in said pocket and inclined outwardly thereof toward said vertically directed friction surface and at an acute angle to said horizontally directed friction surface, a wedge in said pocket and having vertically and horizontally directed friction faces frictionally engageable respectively with said vertically and horizontally directed friction surfaces, an oblique wedging face on said wedge inclined in correspondence with and engaging said wedging surface, spring means in said pocket and projecting into and acting on said wedge and through said wedging face and surface for urging said wedge outwardly and vertically of said pocket and said friction faces and surfaces into frictional engagement, and means carried by said wedge

and engageable with means on said bolster for limiting movement of said wedge into said pocket along said wedging surface against the force of said spring means.

5. In a snubbed railway truck having a side frame carrying supporting coil springs and on a guide column thereof a vertically directed friction surface, a bolster assembly comprising a bolster supported on said springs and having a pocket in a side thereof opening toward said friction surface, a horizontally directed friction surface defining a vertical extremity of said pocket, an oblique wedging surface in said pocket and inclined outwardly thereof toward said vertically directed friction surface and at an acute angle to said horizontally directed friction surface, a wedge in said pocket and having vertically and horizontally directed friction faces frictionally engageable respectively with said vertically and horizontally directed friction surfaces, an oblique wedging face on said wedge inclined in correspondence with and engaging said wedging surface, spring means in said pocket and inclined relative to said wedging and vertically directed surfaces, said spring means acting on said wedge and through said wedging face and surface for urging said wedge outwardly and vertically of said pocket and said friction faces and surfaces into frictional engagement, and means carried by said wedge and engageable with means on said bolster adjacent said pocket for limiting movement of said wedge into said pocket along said wedging surface against the force of said spring means.
6. In a snubbed railway truck having a side frame carrying supporting coil springs and on guide columns thereof of vertically directed friction surfaces at sides of a bolster opening therein, a bolster assembly comprising a bolster supported on said springs and having pockets in opposite sides thereof each opening toward one of said friction surfaces, a horizontally directed friction surface in each of said pockets, an oblique wedging surface in each pocket, said wedging surfaces diverging relatively toward an end of said bolster and each including with the horizontally directed surface in its pocket an acute angle, identical wedge means each in one of said pockets and each having horizontally and vertically directed friction faces each frictionally engageable with the adjoining correspondingly directed friction surface and an oblique wedging face inclined in correspondence and engaging the adjoining wedging surface, spring means in each of said pockets and projecting into and acting on said wedge means therein through the related wedging face and surface, said spring means together urging said wedge means vertically and outwardly of said pockets and said friction faces and surfaces into frictional engagement, and means on each of said wedge means overlapping and engageable with a side of said bolster adjacent its pocket for limiting movement of said wedge means into said pocket along the wedging surface engaged thereby.
